UNITED STATES PATENT OFFICE

125,950

DESIGN FOR A TEXTILE FABRIC

Rose Faller, New York, N. Y., assignor to Stehli & Co. Inc., New York, N. Y., a corporation of New York

Application January 30, 1941, Serial No. 98,531

Term of patent 3½ years

To all whom it may concern:

Be it known that I, Rose Faller, a citizen of the United States, residing in the city of New York, in the county of Bronx and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

ROSE FALLER.
